UNITED STATES PATENT OFFICE.

PHILLIP McMAHON, OF MITCHELL, SOUTH DAKOTA.

RAILWAY-RAIL.

1,147,109.

Specification of Letters Patent. Patented July 20, 1915.

Application filed April 15, 1913. Serial No. 761,369.

To all whom it may concern:

Be it known that I, PHILLIP McMAHON, a citizen of the United States, residing at Mitchell, in the county of Davison and State 5 of South Dakota, have invented a certain new and useful Railway-Rail, of which the following is a specification.

The object of my invention is to provide a railway rail of simple and durable construction so constructed and arranged as to furnish a continuous rail member for the 10 wheels of cars to travel over.

A further object is to provide such a rail so constructed and arranged that when the 15 tread portion of the rail becomes worn, the worn part may be removed and replaced without removing the base of the rail from the ties and without removing the larger part of the rail.

20 My invention consists in certain details, in the construction, arrangement and combination of the various parts of the device, whereby the objects contemplated are attained, as hereinafter more fully set forth, 25 pointed out in my claim and illustrated in the accompanying drawings, in which:

Figure 1 shows a perspective view of a railway rail embodying my invention. Fig. 2 shows a perspective view of the base portion 30 of the rail, and Fig. 3 shows a perspective view of one of my tread portions.

In the accompanying drawings, I have used the reference numeral 10 to indicate generally the base of a rail which is of ordinary construction. Extending upwardly from the portion 10 is the shank 11 which is provided with a longitudinal V-shaped slot 12. At the upper edges of the V-shaped portion are laterally extending flanges 13. 35 The tread portion of my improved railway rail is made in two halves, the tread portion being divided longitudinally. Each half comprises a tread body 14 substantially half as wide as the ordinary tread portion 40 of a rail. Extending downwardly from the lower inner edge of each tread portion 14 is a flange 15 substantially V-shaped in cross section but slightly concave or dished out on its inner surface.

45 I place two of my tread portions together with the flanges 15 adjacent to each other and extending down into the V-shaped slot 12. On account of the fact that the adjacent surfaces of the flanges 15 are slightly 50 concave there is a narrow space between the

flanges 15, which space I have indicated in Fig. 1 by the reference numeral 16. I preferably alternate the joints between the members 14 on one side of my rail with the joints between the members 14 on the other side of the rail. On the inner surface of each portion of the shank 11 I form a longitudinal groove 21 to receive a longitudinal ridge 22 on each shank 15. On account of the construction of the groove 21 and ridge or bead 22, if the tread portion and flange 15 of one half rail should break at some point between the fish plates, the broken ends of the flange 15 would be locked between the portions 11 and could not work upwardly 60 leaving a bad projecting point. It will be understood that the shanks 15 are somewhat resilient. It follows that on account of the construction shown one shank 15 may be installed in the V-shaped channel with its 65 bead or edge 22 received in the proper groove 21, and therefore the other flange may be forced downwardly into position. On account of the concavity of the adjacent faces of the flanges, the flanges during the 70 installation may be sprung together to accommodate the ridge 21 on the second flange 15, and to permit said ridge to pass into the proper groove 22.

Instead of ordinary fish plates, I employ 75 fish plates of a modified form comprising the body portions formed of vertical plates 17. At the lower edge of the body portions 17 is a downwardly and outwardly extending plate member 18 at the outer edge of 80 which is a portion curved downwardly and then inwardly which I have indicated by the reference numeral 19. The fish plates are preferably formed with slightly thickened 85 portions at their upper ends so that when installed the bodies of said fish plates stand apart slightly from the shank 11 as shown 90 in Fig. 1. I have provided bolts 20 extending through the body members 17 of the fish plates and through the walls of the 95 shanks 11 and through the flanges 15. The 100 fact that the upper edges of the fish plates are thickened causes the bodies thereof to be sprung toward the shanks 11 when the nuts are screwed upon the bolts 20, and the resiliency 105 of the fish plates causes them to exert yielding pressure against the nuts, thus serving as nut locks.

In the practical use of my improved railway rail, the arrangement of the tread por- 110

tion in longitudinally divided halves makes it possible to make a continuous rail for the wheels of the cars to travel on. This is made possible by alternating the joints as above set forth. The purpose of the concave surface flange 15 is to permit the resiliency of the rail to force together the upper adjacent edges of the tread portions 14. It will readily be seen that any tread portion 14 which may be worn or broken may be easily and quickly removed and replaced. This can be done without removing the base of the rail from the ties.

It is well known that rails usually wear more on one side. It is however a fact with the ordinary rails that, when one side has worn to a certain extent, it is necessary to remove the entire rail and the rail is thereafter useless except for junk.

Where my improved railway rail is used the worn portion of the tread of the rail may be removed but the base portion may be retained for many years. Only the worn half of the tread portion need be removed and the other half of the tread may be re-

tained until it becomes too worn for further use.

I claim as my invention:

In a device of the class described, a rail base, a web thereon provided with a V-shaped channel, a two-part tread portion, each part thereof comprising a body, and a downwardly extending resilient flange, the flanges of the two parts being designed to be placed adjacent to each other and received in said V-shaped portion being formed with coacting longitudinal ridges and grooves in their adjacent surfaces, said parts being so arranged that when one flange is installed in said channel the other flange may be forced into the channel and on account of the resiliency and the concave faces of the flanges, they may be sprung together during such installation to accommodate the ridges.

Des Moines, Iowa, March 21, 1913.

PHILLIP McMAHON.
